CLAIM

The ornamental design for a bottle handle, as shown and described.

DESCRIPTION

FIG. 1 is a top, front, right perspective view of a bottle handle.

FIG. 2 is a top, rear, left perspective view thereof.

FIG. 3 is a top plan view thereof.

FIG. 4 is a bottom plan view thereof.

FIG. 5 is a front elevation view thereof.

FIG. 6 is a rear elevation view thereof.

FIG. 7 is a left elevation view thereof.

FIG. 8 is a right elevation view thereof.

FIG. 9 is a top, front, right perspective view of the bottle handle shown in an environment of use; and,

FIG. 10 is a top, rear, left perspective view of the bottle handle shown in an environment of use.

The broken lines showing a bottle illustrate environment and form no part of the claimed design.

1 Claim, 10 Drawing Sheets
